UNITED STATES PATENT OFFICE.

THOMAS DAVIES, OF JEROME, ARIZONA.

HOLLOW-DRILL STEEL-PUNCHING MACHINE.

1,232,235.

Specification of Letters Patent.

Patented July 3, 1917.

Application filed July 22, 1916. Serial No. 110,789.

To all whom it may concern:

Be it known that I, THOMAS DAVIES, a citizen of the United States of America, residing at the city of Jerome, county of 5 Yavapai, and State of Arizona, have invented a new and useful Hollow-Drill Steel-Punching Machine, of which the following is a specification.

My invention relates to a new hollow drill 10 steel punching machine; and the objects of my invention are:

First, To provide a machine for enlarging the axial aperture of the drill bit end of heated hollow drill tool steel to enable the 15 water and air passageway through the steel to be kept open during the rock cutting on the end of hollow drill steel, or during the resharpening of dulled hollow steel drills.

Second, To provide means for keeping the 20 hollow steel punching and enlarging pin cool.

Third, To provide means for automatically gripping and holding heated, hollow drill steel of different sizes in axial alignment with the axial aperture enlarging pin.

Fourth, To provide means for cushioning the reciprocating punching strokes of the punching pin.

Fifth, To provide means for removably 30 holding and for quickly changing used and worn punching pins for new ones. And

Sixth, To provide a simple, easily operated, thoroughly practical hollow steel punching machine that will very materially 35 reduce the cost of resharpening hollow drill steel and that always enlarges and leaves the axial aperture through the drill steel open and to the size desired after the drill bit at its end is formed and sharpened.

40 I attain these objects by the mechanism illustrated in the accompanying drawings, in which:

Figure 1, is a side elevation of the improved hollow steel punching machine, and 45 showing a drill steel in position for the punching operation.

Fig. 2, is a vertical, longitudinal sectional view through the two cylinders and parts connected therewith, constituting the punching mechanism, the drill steel vise and its operating cylinder being omitted.

Fig. 3, is an end view of the drill steel clamping vise.

Fig. 4, is a side view, partly broken away, 55 of the pneumatic cylinder and piston, which operates the movable jaw of the vise.

Fig. 5, is a plan view of the vise.

Fig. 6, is a side view partly in section of a drill steel, showing the punching pin inserted in the forward end thereof. And 60

Fig. 7, is an end view of the cutting end of a drill steel.

Similar letters of reference refer to similar parts throughout the several views.

In the present art of drilling holes in rock 65 with rock drilling engines using hollow tool drill steel through which water or air or water commingled with air is conveyed to the cutting point of drill bits and to the bottom of holes in rock as they are drilled, 70 to allay the rock dust and force it from the hole being drilled, hollow steel is used in the form of bars varying in length from about a foot or two to about fifteen or more feet. These bars of hollow steel are generally 75 from three-quarters of an inch to an inch and a half in diameter, depending on the size of drilling engine used, and these bars as most generally used are round in cross section and are known as round hollow drill 80 steel, and each bar has an axial aperture formed through it from end to end of from about a quarter of an inch to about three-eighths of an inch in diameter, depending on the size or diameter of the bar. 85

One end of each bar that is to be made into a rock cutting drill is arranged and adapted to be clamped in the chuck of the drilling engine; the opposite end is heated to a forging heat and is enlarged somewhat 90 and a rock cutting bit that has several V-shaped rock cutting lips, four being most generally used, these rock cutting lips radiating in a circle from the center of the hollow steel to the periphery of its enlarged 95 end portion, is forged on it. A view of such a hollow drill is shown in Figs. 1, 6, and 7.

In order that the function of my hollow steel punching machine may be clearly understood relative to the forming of rock cutting bits on one end of new bars of hollow drill steel, and to the resharpening of drills that have been worn dull by use in drilling holes in rock, I will make this explanation:

In large ore mining mines several hundred 105 drills are worn dull every day and have to be resharpened, and those that have been worn too short or broken have to be replaced by new ones. It is necessary when resharpening a drill or when forming a new one that the axial aperture in the end of the bit that the rock cutting lips are formed on, be kept 110

open preferably to the full size or a trifle larger than the size of the aperture through the bar. These drills are sharpened in drill sharpening machines, of which there are a number in common use, and if something is not used the hole will be wholly or partially closed, which would render it inoperative for the use of dust laying fluid.

The commonest way of keeping the hole open is to drive a cold steel pin into the heated drill bit end of the steel just before it is subjected to the lip forging and sharpening dies of the sharpening machine, and then the sharpening action is completed to instantly withdraw the pin by driving or pulling the pin out, and as the hot end of the drill cools, it shrinks on the cold pin and it requires force and time to drive or pull it out.

My present invention provides a machine in which the drills the instant they are heated to a resharpening heat, can be quickly placed, gripped and centered in axial alignment with the longitudinal axis of the drill bar, and the hole in its heated end be almost instantly enlarged to a size that will still leave it of the same or a trifle larger diameter than the hole through it and be released and discharged and placed in a drill sharpening machine without perceptibly losing its drill sharpening heat.

Consequently reheating is not necessary, and the hole does not have to be again touched after the drill is resharpened.

My machine automatically centers and automatically moves the pin to enlarge the hole in the drills, and its action is a punching pressure force instead of a blow, in moving the enlarging pin into the end of the drills, and my machine thus keeps the texture of the steel in a uniform condition, and it effects a saving of about fifty percent in the time and labor required to resharpen a drill over the common method of driving a pin into the hole by hand and of then forcing it out by hand.

The detail description of the construction and operation of my invention is as follows:

Referring to the drawings,—

Fig. 1 illustrates a hollow steel punching machine embodying my invention. In this Fig. 1, as well as in all of the other figures of the drawings, the numeral 1 designates the foundation supporting stand or pedestal of my machine. This pedestal stand may be made of any suitable material and be of any suitable shape. I preferably however make this stand of structural steel or iron, the frame of which consists of angle beams 2, welded together at their top ends at 3, and riveted at their lower ends to projecting foot plates 4, that extend all around the lower ends of the frame. This stand is in the form of an elongated square flat topped tapering 65 sided form, and the structural iron frame is

made in this form and is covered on the top and front side and on its ends with sheet iron 5, which is riveted to the members of the frame. The foot plates of this pedestal stand are provided with holes, that are adapted to receive lag screws or bolts, by which it may be rigidly secured to a plank floor or to a suitable foundation.

Upon this pedestal stand I mount the several operating parts of my hollow drill 75 punching machine, which parts in the main comprise the pin operating cylinders 7 and 8, which are assembled and connected together by a yoke 9, and the drill bit vise 11 and its operating cylinder 12. These cylinders are provided with lugs 10 that are arranged to enable them to be secured to the stand. The connected cylinders 7 and 8 are connected together by the yoke 9, in axial alignment, and they are secured to the top 85 of the stand. Each cylinder contains a single reciprocating piston rod 13 and two independent piston heads 14 and 15, in each cylinder. The piston rod 13 extends through the front cylinder 7 into the rear cylinder 8. 90 The front cylinder 7 I term the piston reciprocating cylinder, and it is provided with a rear end integral cylinder head 16, and a removable cylinder head 16^A. Each of these cylinder head portions is provided with a 95 stuffing box 16^B and a gland 17, which is threaded to the stuffing box and a packing follower 18. The piston rod 13 extends through both of these stuffing boxes, and the piston head 14 is threaded to a portion of 100 the piston rod within the cylinder 7 that is threaded to receive it, while the piston head 15 is reciprocally mounted within the cylinder 8, and is secured to a reduced portion of the piston rod by a nut 19. The piston heads 105 are provided with piston rings 20 and 21. The front end of the piston rod is provided with a chuck 22, which is arranged to receive and to releasably hold a punching pin 23. This punching pin 23 is a round slightly 110 tapering pin of steel or other suitable metal, the outer end of which is pointed, while the inner terminal end of this punching pin is preferably provided with a flat enlarged head portion 23^A. The chuck may be of 115 any suitable construction to properly grip and hold the pin.

I preferably however have constructed a chuck having a hollow sleeve body portion 24, that is fitted snugly but removably to a 120 reduced shouldered portion at the adjacent terminal end of the piston rod, which is squared off flat. This body portion of the chuck is secured to it preferably by a tapering pin 25, that is extended at right angles 125 through the body of the chuck and the end of the piston rod. The inner peripheral wall of the outer end portion of this body portion is threaded and a plug cap 26 is threaded into it. This cap 26 has an axial 130

aperture 27 through which the tapering end of the punching pin is inserted from the inner side of the cap, which has to be removed from the body of the chuck in order to place the pin through the aperture in its end.

The inside flat surface of the head 23^A of the punching pin, lies flat against the end of the plug cap, and this plug cap is so arranged relatively to the body of the chuck and the terminal end of the piston rod that when it is screwed into the body of the chuck it moves and clamps the outside flat surface of the head of the punching pin against the flat square end of the piston rod, which acts as a rigid abutment for it and allows the piston rod to force the punching pin into the hollow drill steel through the medium of the expansive fluid in the piston reciprocating cylinder 7, acting on the piston 14.

My invention however contemplates broadly the use of any form or shape and of any kind of a punching pin and of a chuck for holding the same that can be properly attached to the end of the piston rod. The cylinder 7 is preferably connected to and its piston is reciprocated by a supply of compressed air, although any other suitable expansive fluid may be used if desired. The opposite ends of this cylinder are provided with ports 28 and 29, to which one end of air supply pipes are connected at a short distance above the cylinder to a four-way valve 30, that is arranged between them, from which a pipe 31 extends down to the stand and connects to a general air supply pipe 32 that extends along the side of the stand and is secured to it and that also furnishes a supply of air to the vise operating cylinder 12. This general air supplying pipe is provided with a three-way valve 33, that is connected by a pipe 34 to a supply of compressed air of suitable pressure to operate the pistons of the cylinders 7 and 12. The four-way valve is operated by a hand lever 35 to admit air to the opposite ends of the cylinder 7 and its piston.

The cylinder 8 is an oil holding piston cushioning cylinder. It is provided with a stuffing box 36 that surrounds the piston rod 13. This cylinder receives a supply of oil through the two-way valve 37, which oil flows to the opposite ends of the cylinder 55 through the pipes 38 that extend from the valve 37 to ports in the opposite ends of the cylinder, and which admit oil to first one side of the piston head 15 and then to its opposite side. The pipes 38 constitute a bypass which permits the oil to flow automatically through them from one side of the piston head to its opposite side.

The oil acts to cushion the reciprocating strokes of the air driven piston head 14 in the cylinder 7. A sufficient amount of oil is

kept in the cylinder to effectually cushion the strokes of the piston 14. Only enough oil is added from time to time to replace the leakage through the stuffing box 36. As the punching pin repeatedly enters and enlarges the axial aperture in the rock cutting bit end of hollow drill steel heated to a drill sharpening and forging heat, it gets very hot and it is necessary that some means be employed to cool it and to keep it at a practically operating temperature.

My invention contemplates any suitable means for accomplishing this object. I preferably however, employ a fluid for cooling the pin and find by experience that a jet of compressed air discharged continuously on the pin when it is being used in enlarging the axial aperture in heated hollow drill steel makes an effectual cooling medium, and I convey a stream of air to and discharge it directly against the pin from the general air supply pipe 32 through a small pipe 39 that is connected at one end to the supply pipe and its opposite end is bent to discharge the air directly against the heated punching pin.

This pipe is provided with a valve 40 and the air discharging end of the pipe is provided with a flattened nozzle 41. The drill steel holding vise is mounted on the front outer end portion of the stand, in front of the punching pin and at a distance from it to allow the end of the drill steel that is clamped just back of the heated end to be within the reciprocal stroke of the punching pin. This vise consists of two plates 42 that are each provided with feet portions 43 which are bolted to the top of the stand 1. These vertical plates 42 are placed at a distance apart necessary to receive between them an interchangeable but fixed block shaped jaw 44, which is bolted and clamped rigidly between them by bolts 45 that extend through both plates and the jaw and clamp all three together.

The two plates are provided with recesses 46 that are arranged in alignment with the longitudinal axis of the punching pin 23 and its actuating piston 14. These recesses are large enough to receive and to admit to the largest sizes of drill steel used in drilling engines, and the front edge of the fixed jaw extends close to the vertical plane of the axial center of the punching pin, and at its center it is provided with a recess of semicircular form to fit the cross section of either round, hexagonal or other forms of tool steel. A half round recess is shown as hollow round steel is preferably used.

I also place between the vertical plates 42 a movable jaw 47 which is mounted to swing up and down to and from the fixed jaw. This swinging jaw fits loosely between the plates and is pivoted to them by a pin 48 that extends through them and the jaw.

This jaw has a drill steel engaging recess 49 that is of curved form and that is positioned opposite to the recess in the fixed jaw, and which may be made to fit any 5 form of cross section of drill steel, but which is illustrated adapted to clamp round tool steel in the recess of the fixed jaw. This movably mounted swinging jaw has a rearwardly extending shank portion that extends beyond the plates over the front side 10 of the stand and to its end one end of a link 50 is pivotally connected. The opposite end of the link is pivotally connected by a pin 51 to the outer end of a piston rod 52, that is reciprocally mounted in the cylinder 15 52 that is secured to the front side of the stand.

This cylinder is vertically positioned on the side of the stand and a supply of air 20 is led to it from the three-way valve 33 in the general supply pipe 32 through a pipe 53 that is connected at one end to the valve and at its opposite end is connected to the bottom of the cylinder. The piston rod 52 extends into the cylinder through a gland 25 ring 54 that is threaded to the cylinder head. The inner end of the piston rod 52 is provided with a piston head 55 that is reciprocally mounted loosely enough to drop 30 quite quickly by its weight against the air below it, which acts to cushion it. The air is admitted to the bottom of the cylinder, while the upper end of the cylinder is open to the atmosphere, through a vent pipe 56 35 that is threaded to the cylinder head, and that prevents any air being compressed above the piston head to interfere with its exerting its full upward pressure against the swinging jaw when air is applied to its 40 under side.

The air entering the bottom of the cylinder forces the piston head and rod and the link upward, and closes the swinging jaw against the fixed jaw or against a drill steel 45 if one is placed in the recess, of the fixed jaw, with great pressure. The fixed block jaw is made thick enough so that its steel supporting recess is long enough to act as a firm and steady support for the drills, 50 and they are firmly and tightly gripped in this air power vise and are held in true axial alinement with the longitudinal axis of the punching pin and its piston rod.

The operation of my hollow steel punching machine is as follows:

The ends of the hollow drills to be resharpened or of the new lengths or bars of hollow steel on one end of which a rock cutting bit is to be formed are heated in a suitable forge to a suitable forging heat. Then 60 an operator takes one in one hand and places it in the recess of the fixed jaw with its heated end projecting into the path of the operative stroke of the punching pin; and 65 at the same time that he places a steel in

the fixed jaw, he opens the three-way valve 33 to admit compressed air into the cylinder 12 which instantly closes the swinging jaw 47 against the drill and clamps it rigidly against the fixed jaw, in which position the center of its axial aperture is in alinement with the longitudinal axis of the punching pin and its actuating piston.

The operator having clamped a steel in the vise, leaves the valve open so that the air pressure exerts a constant pressure on the piston head of the vise cylinder and holds the steel gripped continuously in the vise. The operator then opens the four-way valve 30 to admit compressed air into 75 the rear end of the cylinder, which acting on the piston head 14 moves the piston rod forward in the cylinder and forces the punching pin by a single quite quick forward stroke into the aperture in the heated end of the steel and expands and enlarges it to a tapering hole that is preferably seven-sixteenths of an inch in diameter at its largest end, but that can be made a trifle larger or smaller if desired, as the pin is a 80 taper pin.

The operator then reverses the valve 30 to shut off the air to the rear of the piston 85 14 in the cylinder, and admit it to its front end, which moves it to the rear end of the cylinder, and withdraws the punching pin from the steel, leaving a clean round smooth enlarged tapering hole in the center of its heated end. The operator now instantly releases the steel from the vise by moving 90 the three-way valve to shut off air from the lower end of the piston head. This allows the piston head to drop in the cylinder quite quickly, and as it does so, it forces the air out and back through the pipe 95 53 and out of the open aperture in the three-way valve to the atmosphere.

The operator the instant the steel is released, places the steel in a drill sharpening machine, and it is sharpened with the 100 same heat. The entire operation of gripping a steel, enlarging its aperture in its bit, and releasing it, is accomplished in a few seconds.

A current of cool air is kept constantly 115 discharging against the pin, from the air pipe which keeps it cool enough to be used as fast as the heated drills are submitted to its action.

My invention provides a quick and positively operating machine for so enlarging the rock cutting bit ends of hollow drills that much more accurately and true rock cutting bits and lips are formed on the ends of drill steel, in addition to the saving of 125 about fifty per cent. of the time required in forming and resharpening drills, which is an economic feature of considerable value in mines that have a large number of drills to keep sharpened.

Having described my invention, what I claim as new and desire to secure by Letters Patent, is:

1. A machine for enlarging the axial aperture in the rock drilling ends of hollow drill steel, comprising a fluid actuated piston operating drill steel holding vise, a fluid actuated reciprocating pin arranged and adapted to enter and enlarge said axial aperture, means including a chuck carrying piston rod arranged to removably and renewably support said pin, cushioning means operating on said pistons for reciprocally operating said pin, a piston head secured 5 to the opposite ends of said piston rod, a cylinder surrounding each piston, and means including fluid passageways in said cylinders whereby said pistons operate and cushion the reciprocal movements of said 10 piston rod and pin.

2. In a hollow steel punching machine, the combination with the supporting stand and the punching pin actuating and cushioning cylinders and their operative mechanism, with the hollow steel gripping vise comprising the side plates and the fixed and the movable jaw, the compressed air cylinder and its piston, the link connecting said movable jaw to said piston, and means 25 including a three-way valve for providing said cylinder with a supply of compressed air, said cylinder being arranged to force said movable jaw to grip and rigidly hold a drill steel against said fixed jaw with a 30 constant pressure for a period of time.

3. In a hollow steel punching machine, the combination of the supporting stand, the drill steel gripping vise secured thereon and the fluid actuated cylinder mounted on said 40 stand, and arranged to open and close said vise to grip and release heated hollow drill steel, with a punching pin reciprocally mounted to enter the axial aperture of the rock drilling end of heated drill steel 45 clamped in said vise, the connected cylinders secured on said stand, the piston rod extending through one cylinder into the other, the chuck on the outer end of said piston rod arranged to releasably hold said punching 50 pin, the piston head on said piston rod in each cylinder, and means including the operative pipes and valves connected to said cylinders for reciprocating and cushioning the reciprocal movements of said piston and 55 punching pin.

4. In a machine of the character described, a supporting stand, a pair of cylinders in alinement secured on said stand, a yoke connecting said cylinders together at 60 a short distance apart, a piston rod extending entirely through one cylinder and into the other cylinder, a piston head in each cylinder on said piston rod, a chuck on the outer end of said piston rod, a punching 65 steel pin releasably secured and held by said

chuck, a drill steel holding vise secured in front of said pin on said supporting stand, said vise having a fixed and a movable drill steel gripping jaw, a compressed air actuated cylinder and piston arranged to operate said movable jaw, means including a valve controlled compressed air supply pipe arranged to supply said chuck piston and pin actuating cylinder and said movable jaw cylinder with a supply of compressed air, and means including a by-pass piping system connected to the chuck and pin actuating cylinder.

5. In a machine of the character described, the combination of a supporting stand comprising a frame of structural metal, a pair of cylinders connected in alinement by a yoke and secured to the top of said stand, one cylinder of which is a piston reciprocating cylinder and the other is a piston cushioning cylinder, a piston rod extending reciprocally through said piston reciprocating cylinder into the piston cushioning cylinder, said piston rod having a piston head on it in each cylinder and a chuck 70 on its outer end, said chuck comprising a sleeve removably pinned to the end of said piston, a plug cap threaded into the end of said sleeve, with a tapering hollow steel enlarging pin arranged to be removably held 75 by said chuck, said pin comprising a long tapering body portion and a head portion, said plug cap being provided with an axial aperture through which the body of said pin projects, and the head of said pin being 80 arranged to fit loosely in said sleeve and be clamped by said plug cap against the end of said piston rod, ports in the opposite end of said chuck and pin actuating cylinder pipes connected at one end to said ports and connected to the opposite ends of a four-way 85 valve, means including a pipe connected to said four-way valve for connecting said cylinder to a suitable supply of compressed air, a pipe connected to the opposite ends of said 90 piston cushioning cylinder, a valve connected to the opposite ends of said pipes, and means including said valve for admitting a supply of oil to said cylinder and for 95 confining it therein to cause it to circulate 100 from one side of said piston to the other through said pipes to cushion the reciprocating strokes of said piston head, the piston rod and the pin, and means including a power operated drill steel gripping vise 105 secured on said supporting stand and arranged 110 to grip and hold heated hollow drill steel with its axial aperture in alinement and in operative enlarging relation to said pin.

6. In a machine of the character described, the combination of the supporting stand, the pair of cylinders secured to the top of said stand connected in alinement and separated, one of which is a piston reciprocating air driven cylinder and the other 120

130

the piston oil cushioning cylinder, means including a four-way valve for operatively reciprocating the piston in said piston reciprocating cylinder, and means including 5 a valve for providing the piston cushioning cylinder with oil and cushioning the reciprocating strokes of said piston, a chuck on the outer end of said piston and a hollow steel axial aperture enlarging pin removably secured 10 in said chuck, with a hollow steel gripping vise and an air power operating cylinder and piston secured on said stand and arranged to open and close said vise, said vise comprising a pair of parallelly arranged 15 plates extending across the top of said stand at right angles to the longitudinal axis of said pin and piston rod, and the piston's reciprocating and cushioning cylinders, said plates being each provided with 20 a fixed jaw removably secured between said plates, said fixed jaw being provided with a drill steel receiving recess arranged to center the axial aperture of hollow steel centrally in alinement with the longitudinal 25 axis of said pin, and adapted to fit steel of

any form of cross section, a swinging jaw pivoted between said plates, a link pivotally secured at one end to said swinging jaw and pivotally connected at its opposite end to one end of a piston rod, the opposite end of which extends reciprocally into a cylinder 30 and is provided with a piston head, a cylinder adapted to receive said piston head and rod reciprocally, an axial aperture in the top of said cylinder open to the atmosphere, 35 and means including a three-way valve and piping connected to the bottom of said cylinder and arranged to be connected to a supply of compressed air for operating said piston to move said swinging jaw to grip and hold 40 a heated drill steel against said fixed jaw and in operative axial aperture enlarging relation to said pin.

In testimony whereof I affix my signature in presence of two witnesses.

THOMAS DAVIES.
